MACHINE FOR PRINTING FLOOR AND
WALL COVERINGS

Thomas Pesci, Raritan, N. J.

Application February 26, 1934, Serial No. 712,933

20 Claims. (Cl. 101—199)

My invention relates to improvements in a machine for printing floor and wall coverings, such as linoleum, oil cloth, and goods of like character, and particularly relates to a flat top machine, having vertically reciprocating heads carrying printing blocks, and horizontally reciprocating rolls for applying the printing liquid to the blocks.

The object of my invention is to print upon the goods a reproduction of marble, the grain of wood, and various shading effects and designs, by applying the same to the printing surface of a printing block of a flat top machine.

A further object is to apply the desired reproduction to the surface of a roll, by engraving, or by any well known photographic process, and transferring an impression to the printing block by passing the roll over the surface of the latter, and then impressing the block upon the goods.

20 A further object is to provide a novel printing block having a smooth resilient printing surface for receiving said reproduction from the roll and for transferring it to the goods.

25 A further object is to substitute an engraved roll for one of the usual type of rolls now used for applying the printing liquid to the printing blocks of a flat top machine.

30 A further object is to provide a novel arrangement of the doctors, or scrapers, for applying the printing liquid to the engraved roll.

A further object is to provide mechanism for automatically shifting the doctors relatively to the direction of rotation of the roll.

35 A further object is to provide cams located upon the reciprocating heads for engaging and operating the shifting mechanism for the doctors.

These together with various other novel features of construction and operation of the parts, which will be more fully hereinafter described 40 and claimed, constitute my invention.

Referring to the accompanying drawings, Fig. 1 is a vertical longitudinal section, partly in elevation, of a portion of a flat top printing machine, embodying my invention.

45 Fig. 2 is a partial plan view of Fig. 1.

Fig. 3 is a vertical sectional view on line 3—3 Fig. 1.

Fig. 4 is a partial sectional view similar to Fig. 1, showing the parts in a different position, and 50 drawn on a larger scale.

Fig. 5 is an end elevation of the carriage, shown in Fig. 4.

Fig. 6 is a transverse vertical section on line 6—6 Fig. 5.

55 In the drawings in which like reference char-

acters refer to like parts, 10 represents the frame of a flat top printing machine, such as now in general use. The patent to Eisenhardt No. 476,135, May 31, 1892, illustrates the type of machine to which my invention may be applied.

A table 12 is supported between the side members of the frame 10, and the table supports the goods 13 to be printed. Feed bands 14 are mounted in guides 15, supported upon the frame, for advancing the goods intermittently, as shown in Fig. 3.

A series of reciprocating heads 18, 19 and 20 are arranged throughout the length of the machine. The heads 18 and 20 are provided with printing blocks 21, having printing surfaces for printing various colors and designs upon the goods, in the usual manner.

The head 19 has a block 22 which is provided with a novel printing surface, comprising a pad 23, formed of resilient material and forming a smooth printing surface, more fully hereinafter described.

The heads 18, 19 and 20 are secured upon cross beams 24, 25 and 26, which are supported upon end members 28, slidably mounted in guides 29, located on opposite sides of the frame. The end members 28 have rollers 30, which are engaged by cams 31, for reciprocating the heads.

An engraved roll 32 is provided for applying the engraved reproduction to the printing surface of the pad 23. A roll 33 of the usual type, is provided for applying printing liquid to each of the blocks 21. The rolls 32 and 33 are mounted upon troughs 35 and 36 and dip into the printing liquid contained in the troughs, and apply the liquid to the printing surfaces.

The troughs 35 and 36 are provided at their opposite ends with wheels 37, which are mounted on tracks 38, extending lengthwise of the frame 10. The rolls have shafts 39 on which are secured gear wheels 40, which mesh with idler gear wheels 41, which latter engage racks 42, extending parallel with the tracks 38. The troughs 35 and 36 are secured on carriages 44 and 45, which are coupled together by links 46. The carriages are reciprocated relatively to the heads, from the position shown in Fig. 1 to that shown in Fig. 4, by any suitable mechanism, such as the arms 47, pivoted to the frame 10, and actuated by cranks 48 and connecting rods 49, in a manner well known in the art.

The operating mechanism is so timed that the heads will be at rest, in the elevated position relatively to the goods, as shown in Fig. 1, when the carriages are moved in one direction for rolling

the surface of the rolls in contact with the printing surfaces of the heads.

After the heads have been moved into printing engagement with the goods, as shown in Fig. 4, 5 and again are in the elevated position, the carriages are moved in the opposite direction. During the reciprocating movements of the carriages, the gear wheels 40 and 41 rotate the rolls in the proper direction so that the surface of the 10 rolls will always be in rolling contact with the printing surfaces of the blocks.

The roll 32 has its surface engraved with reproductions of marble, wood graining, or shading, and the impression is transferred from the roll 15 32 to the printing surface of the pad 23 as the roll 32 is moved over said printing surface.

The pad 23 is formed with raised printing surfaces arranged to form a design corresponding to the design formed upon the goods by the other 20 printing blocks 21, so that the markings on the pad 23 will properly register with the design as formed on the goods.

The pad 23 is formed of rubber, gelatine, or any other resilient material impervious to oil and gasoline, and which will present a smooth printing surface. Synthetic rubber is a suitable material for the construction of the pad. The pad is molded into figures, or blocks to correspond to the design to be printed upon the goods. The 25 pad so molded is then cemented upon the block 22.

The transferring of markings by means of an engraved roll to the pad 23 requires the employment of doctors 52 and 53 which are movably mounted relatively to the roll 32, and means for alternately shifting the doctors into and out of contact with the roll 32, so that the latter may 30 rotate in different directions.

Fig. 1 shows the doctor 53 in contact with the roll 32, which will rotate anti-clockwise as it is moved to the right relatively to the pad 23.

Fig. 4 shows the doctors shifted to the opposite position, with the doctor 52 in contact with the roll 32, which latter will rotate clockwise, as it is moved to the left relatively to the pad 23. The engraved surface of the roll 32 would be 45 damaged if the roll rotated in a direction in which the surface of the roll would travel toward the edge of the blade of the doctor, therefore it is essential that the doctors be positioned to allow the engraved surface of the roll to pass freely under doctor, as above described.

Heretofore the doctors were mounted in spaced relation to the rolls for removing the excess liquid. The rolls 33 are only provided for applying the liquid to the printing blocks 21, and they 55 can be rotated in either direction as the doctors are mounted in spaced relation to the rolls.

The use of an engraved roll 32 necessitates the doctors being set with their blades in contact with the roll in order that they may remove the liquid 60 from the surface of the roll. Therefore the edges of the doctors must be alternately moved into and out of contact with the roll, according to the direction of rotation of the latter.

The doctors 52 and 53 are located upon opposite sides of the roll 32, and are pivotally mounted upon shafts 55, secured in bearings 56, attached to the inner surfaces of the walls of the trough 35. Lugs 57 are secured to the doctors, and said lugs are bifurcated and embrace the 65 shafts 55, so that the doctors may be readily detached and removed from the trough.

Each doctor consists of a blade 60, secured between plates, or doctor holders, 61 and 62, by 70 bolts 63. The lower holder 62 is provided with

the above mentioned lugs 57. The upper holder 61 is provided with lugs 64, to receive connecting rods 65 for tilting the doctors about the shafts 55.

End brackets 68 are secured to the opposite ends of the trough 35 by bolts 69. Shift bars 5 70 are slidably mounted upon bearings 71 and 72 formed upon the brackets 68. Pivot plates, or levers, 74 are loosely pivoted on shafts 75, secured upon the brackets 68. The levers 74 each have an upper arm 76 which is bifurcated and 10 embraces a pin 77, secured to the central portion of the shift bar 70. The lower arm 78 of the lever 74 has apertures formed therein to receive the connecting rods 65. When the shift bar 15 70 is moved, the lever 74 and the rods 65 will 20 shift the doctors alternately into and out of contact with the roll 32.

The shift bars 70 are moved in the bearings 25 71 and 72, to shift the doctors, by means of cams 80 and 81 located upon the vertically reciprocating frames 24 and 26 carrying the heads 18 and 20, which latter are located upon the opposite sides of the head 19 carrying the pad 23. When the engraved roll 32 has moved over the surface of the pad 23 the carriages will come 25 to rest with the trough 35 positioned between the heads 18 and 19, and then the heads all move into printing contact with the goods 13. The movement of the heads toward the goods causes the cam 80 to engage the shift bars 70 and move 30 them into the position shown in Fig. 1, with the doctor 52 out of contact with the roll and the doctor 53 positioned in contact with the roll, so that when the carriages move to the right and the roll is rotated anti-clockwise, the surface of the roll will pass under the blade of the doctor 53 without injuring the engraved surface 35 of the roll.

When the carriages come to rest with the trough 35 positioned on the opposite side of the head 19, as shown in Fig. 4, the heads will be 40 again moved into contact with the goods and the cam 81, carried by the head 20, will have engaged and moved the shift bar 70 and the doctors into the position shown in Fig. 4, in which the doctor 52 is in engagement with the roll and the doctor 53 is out of engagement with the roll, so that the latter can rotate in a clockwise direction, when the carriages move to the left for 45 passing the roll under the pad 23.

The shift bars 70 are each provided at their 50 opposite ends with adjusting devices, in the form of screws 82 and lock nuts 83, by means of which the shift bar can be adjusted so that the cams 80 and 81 will move the shift bar to its proper 55 positions for shifting the doctors relatively to the roll 32.

Various changes may be made in the construction and operation of the parts without departing from my invention.

I claim:—

1. A printing machine having in combination, a reciprocating head having a transfer printing surface, a roll having a design formed thereon, means mounting said roll for movement in opposite directions relatively to the head, a doctor movably mounted relatively to said roll, and shifting mechanism arranged for shifting the doctor into and out of operative position with the roll.

2. A printing machine having in combination, a reciprocating head having a flat transfer printing surface, a roll having a design formed thereon, mechanism arranged for reciprocating the roll in contact with the head, a doctor arranged 75

- for engagement with the surface of the roll, and automatically controlled shifting mechanism operatively associated with the doctor for shifting the latter relatively to the roll.

5. A printing machine having in combination, a reciprocating printing head having a transfer printing surface, a roll having an engraved surface, mechanism arranged for rotating the roll with the engraved surface thereof in contact with the printing surface of the head, a doctor positioned adjacent to said roll, and shifting mechanism arranged for shifting the doctor into engagement with the surface of the roll when the roll is rotated in one direction and for shifting the doctor out of engagement with the surface of the roll when the latter is rotated in the opposite direction.

10. A printing machine having in combination, a reciprocating head having a flat transfer printing surface, a roll having an engraved surface, mechanism for rotating the roll in opposite directions over the printing surface of the head, doctors located at opposite sides of said roll, and shifting mechanism operatively associated with the doctors and arranged for alternately engaging and disengaging the doctors with the roll.

15. A printing machine having in combination, a reciprocating head, a pad upon said head, said pad formed of resilient material and forming a flat transfer printing surface, a roll having markings thereon, a trough, means mounting the roll upon the trough, means for moving the roll in contact with said printing surface for transferring said markings to the pad, a doctor movably mounted upon the trough and in operative relation with the surface of the roll, and shifting mechanism mounted upon the trough and arranged for moving the doctor into and out of engagement with the surface of the roll when the latter is moved in different directions.

20. A printing machine having in combination, a reciprocating head, a pad of resilient material upon the head and forming a flat printing surface, a roll having engraved markings upon its surface, doctors movably mounted in operative relation with the roll, and shifting mechanism arranged for alternately engaging the doctors with the surface of the roll.

25. A printing machine having in combination, a reciprocating head, forming a transfer printing surface, a pad of resilient material upon said head, a roll having engraved markings thereon, mechanism arranged for reciprocating the roll in contact with said pad, doctors located on opposite sides of the roll, shifting mechanism operatively associated with the doctors and arranged for alternately engaging and disengaging the doctors with the surface of the roll, and means operatively associated with said shifting mechanism and arranged for actuating the latter to shift the doctors.

30. A printing machine having in combination, a reciprocating head having a flat printing surface, a roll having engraved markings thereon, mechanism for reciprocating the roll in contact with said printing surface, doctors located on opposite sides of the roll, shifting mechanism arranged for engaging and disengaging the doctors with the surface of the roll, and engaging means located at opposite sides of the head and operatively associated with said shifting mechanism and arranged for actuating the latter for shifting the doctors relatively to the roll.

35. A printing machine having in combination, a reciprocating head having a flat printing surface, a roll having engraved markings thereon, mechanism for reciprocating the roll in contact with said printing surface, doctors located on opposite sides of the roll, shifting mechanism arranged for reciprocating the roll in contact with said printing surface, doctors movably mounted upon the trough, mechanism arranged for reciprocating the trough for passing the roll in contact with said printing surface, doctors movably mounted upon the trough, shifting mechanism mounted upon the trough and arranged for alternately engaging the doctors with the roll, and engaging means arranged for actuating said shifting mechanism.

40. A printing machine having in combination, a reciprocating head having a flat printing surface, a trough, a roll rotatably mounted upon the trough, mechanism arranged for reciprocating the trough for passing the roll in contact with said printing surface, doctors mounted upon the trough, shifting mechanism mounted upon the trough and arranged for alternately engaging the doctors with the roll, and means located upon the machine at opposite sides of said head and arranged for actuating the shifting mechanism.

45. A printing machine having in combination, a series of reciprocating heads, a pad of resilient material upon one of said heads and forming a printing surface, an engraved roll, means for passing the roll over the printing surface of the pad, a trough, means mounting the roll upon the trough, doctors movably mounted upon the trough, and means upon said reciprocating heads and arranged for moving the doctors into and out of contact with said roll.

50. A printing machine having in combination, a series of reciprocating heads having printing surfaces thereon, a roll co-operating with the printing surface of one of said heads, a trough, means mounting the roll upon the trough, mechanism arranged for reciprocating the trough for passing the roll in contact with said printing surface, doctors movably mounted upon the trough, shifting mechanism mounted upon the trough and arranged for alternately engaging the doctors with the roll, and cams mounted upon the reciprocating heads located at opposite sides of the head with which said roll co-operates and arranged for actuating said shifting mechanism.

55. A printing machine having in combination, a reciprocating head having a printing surface thereon, a trough for containing a printing liquid, a roll mounted upon the trough, doctors movably mounted upon the trough and located at opposite sides of the roll, a lever pivotally mounted upon the trough, and connecting rods pivotally connecting one arm of the lever with the doctors and arranged for alternately engaging the doctors with the roll.

60. A printing machine having in combination, a reciprocating head having a printing surface thereon, a trough for containing a printing liquid, a roll mounted upon the trough, doctors pivotally mounted upon the trough and located at opposite sides of the roll, a lever pivotally mounted upon the trough, connecting rods pivotally connected with the lever and the doctors and arranged for alternately engaging the doctors with the roll, a shift bar slidably mounted upon the trough, and a pivotal connection between said bar and said lever.

65. A printing machine having in combination, a reciprocating head having a printing surface thereon, a trough for containing a printing liquid, a roll mounted upon the trough, doctors located at opposite sides of the roll, a shift bar slidably mounted upon the trough and operatively associated with the doctors for alternatively moving the doctors relatively to the roll, means for reciprocating the trough for passing the roll in

contact with the printing surface of the head, and means located at opposite sides of said head and arranged for actuating said shift bar.

16. A printing machine having in combination, a reciprocating head having a printing surface thereon, a trough for containing a printing liquid, a roll mounted upon the trough, doctors mounted upon the trough and located at opposite sides of the roll, a shift bar slidably mounted upon the trough and operatively associated with the doctors, means for reciprocating the trough for passing the roll in contact with the printing surface of the head, adjusting devices upon the shift bar, and means located at opposite sides of said head and arranged for engagement with said devices.

17. A printing machine having in combination, a series of reciprocating heads having printing surfaces thereon, a roll co-operating with the printing surface of one of said heads, a trough, means mounting the roll upon the trough, mechanism arranged for reciprocating the trough for passing the roll in contact with said printing surface of one of said heads, doctors pivotally mounted upon the trough, a shift bar slidably mounted upon the trough and operatively associated with the doctors, and cams mounted upon said heads and arranged for actuating the shift bar.

18. The combination of a trough, a roll mounted upon the trough, doctors located upon opposite sides of the roll, a lever mounted upon the trough, connecting rods connected with the lever and with the doctors, bearings secured upon the trough, shafts secured in said bearings, and bifurcated lugs upon the doctors and embracing said shafts and arranged for removably mounting the doctors upon the trough.

19. The combination of a trough, a roll mounted upon the trough, doctors movably mounted upon the trough, a bracket mounted upon the trough, a shift bar slidably mounted upon said bracket, and means operatively associated with said bar and the doctors and arranged for shifting the doctors relatively to the roll.

20. The combination of a trough, a roll mounted upon the trough, doctors mounted upon the trough and located at opposite sides of the roll, brackets mounted upon opposite ends of the trough, shift bars positioned at right angles to the length of the roll, bearings upon the brackets in which the shift bars are movably mounted, levers pivotally associated with the shift bars, and connecting rods connected with the levers and with the doctors and arranged for moving the doctors relatively to the roll.

THOMAS PESCI.
